TENNIS RACKET STORAGE AND DISPLAY DEVICE

Jacob Stap, 1328 Woodland Drive,
Deerfield, Ill. 60015

Filed June 1, 1973, Ser. No. 366,049

Term of patent 14 years

Int. Cl. D6—06

U.S. Cl. D6—114

FIG. 1 is a perspective view of the tennis racket storage and display device;

FIG. 2 is a side elevational view, the opposite side being a mirror image thereof;

FIG. 3 is a front elevational view; and

FIG. 4 is a top plan view.

I claim:

The ornamental design for a tennis racket storage and display device, as shown and described.
